ATTORNEYS

UNITED STATES PATENT OFFICE.

JOHN T. McCARNEY, OF COLUMBUS JUNCTION, IOWA.

HORSE-POWER.

SPECIFICATION forming part of Letters Patent No. 297,825, dated April 29, 1884.

Application filed February 26, 1884. (No model.)

To all whom it may concern:

Be it known that I, JOHN T. McCARNEY, a citizen of the United States, residing at Columbus Junction, in the county of Louisa and State of Iowa, have invented certain new and useful Improvements in Horse-Powers; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of this invention, and is a vertical section. Fig. 2 is a detail view showing brake.

This invention has relation to friction-brakes for that class of horse-powers which have the master-wheel formed with a central block or hub seated on a perpendicular center-pin; and the invention consists in applying on the line-shaft, under the center-pin, a friction-wheel, rigidly cemented to and turning with the line-shaft, and in proper relation to this friction-wheel a band-brake or friction-brake having an operating-arm extending upward through a passage in the center-pin, and terminating in a handle within easy reach of the driver, all as hereinafter set forth.

In the accompanying drawings, the letter A designates the master-wheel, and B the hub or center bearing thereof, projecting upward from the bridge-beam C, which is secured to the timbers of the frame D. The center-pin is provided with a way or passage, e, in its center or side, which is continued downward through the bridge-beam and central supports.

F represents the line-shaft, having at its opposite ends the bevel-pinions or bevel-wheels g, which engage the bevel-wheels h, the shafts of which extend upward to bearings of the bridge-beam and carry the pinions k, which engage the master-wheel. On the line-shaft, vertically under the center-pin, is keyed a

friction-wheel, L, and around the under side of this wheel extends the friction band or brake Z, which is provided with an arm, V, which extends upward through the passage e of the center-pin, and is provided at its upper end, which projects above the master-wheel, with an operating-handle, whereby the brake can be brought into engagement with the friction-wheel by the driver whenever it is necessary to lessen the speed of the machine or to stop it altogether. The arm may be made in screw form, and in that case should pass through a threaded bearing connected to the center-pin, said bearing engaging the thread of the screw, so that when turned by means of the handle on its end it will raise or lower the brake, applying it or taking it off, as may be required.

I am aware that it is not new to provide a horse-power with a master-wheel having a hub bearing on a center-pin with a perpendicular passage for a rod to operate a friction-brake on the line-shaft, and therefore do not claim such construction, broadly.

Having described this invention, what I claim, and desire to secure by Letters Patent, is—

In a horse-power, the combination, with the master-wheel having a central block or hub seated on a perpendicular center-pin, of the line-shaft F, friction-wheel L, rigidly connected thereto under the center-pin, as shown, the friction-brake Z, constructed as described, having its operating-arm V extending up through a passage, e, in the center-pin, and terminating in a handle, substantially as specified.

In testimony whereof I affix my signature in presence of two witnesses.

JOHN T. McCARNEY.
